UNITED STATES PATENT OFFICE.

ALEXANDER C. DUMONTIER AND ARTHUR PLOURDE, OF DETROIT, MICHIGAN, ASSIGNORS OF THREE-FIFTHS TO HENRY W. HARDING, ARTHUR DUMONTIER, AND WM. M. DWIGHT, OF SAME PLACE.

CHIP-BREAKER.

SPECIFICATION forming part of Letters Patent No. 336,845, dated February 23, 1886.

Application filed September 16, 1885. Serial No. 177,275. (No model.)

To all whom it may concern:

Be it known that we, ALEXANDER C. DUMONTIER and ARTHUR PLOURDE, of Detroit, in the county of Wayne and State of Michigan, have invented new and useful Improvements in Planing-Machine Attachments; and we do hereby declare that the following is a full, clear, and exact description thereof, reference being had to the accompanying drawings, which form a part of this specification.

This invention relates to certain new and useful improvements in the construction and operation of pressure-bars for planing-machines, such pressure-bars being provided with chip-breaker attachments.

The invention consists in the peculiar construction and operation of the parts, by means of which the pressure-bar and its chip-breaker attachments are secured in a radial movement from a fixed point which is adjustable, and by means of which the point of the chip-breaker is always brought, at any point of the radial movement, into the proper position to perform its function. If the pivotal point is too high, the board being passed along the bed of the planer under the chip-breaker and pressure-bar has a tendency, instead of raising the chip-breaker, to wedge it in the opposite direction; therefore our invention is designed to so enlarge such pivotal point and the devices by which the chip-breaker is controlled that under no circumstances can the entering lumber wedge it against its upward motion, and that in its radial movement the point of the chip-breaker will be presented concentric, or nearly so, to the circle described by the revolving knives.

Figure 1 is a plan of a section of a planer showing our attachment. Fig. 2 is a vertical longitudinal section on the line $x-x$ in Fig. 1. Fig. 3 is an enlarged detailed perspective of the various operating parts, and Fig. 4 is a diagram illustrating the operation of the chip-breaker.

In the accompanying drawings, A represents the bed of a planing-machine; and B, the head having cutters C attached thereto and supported upon a suitable mandrel running in

proper boxes secured at each side of the machine above the bed, and these parts are of the ordinary construction and operation.

D is a pressure-bar, the office of which is to rest upon and hold down the board as it is advanced along the bed of the machine to the action of the cutters or planers. This pressure-bar must be vertically adjustable, in order to suit the various thicknesses of lumber presented, and in various machines it is supported or attached in various manners. We prefer to so attach this pressure bar that it may have a radial movement from a fixed point, which latter, however, may be adjusted as desired; and to this end we will now describe our method of supporting and adjusting this pressure-bar, premising, however, that to this pressure-bar there is secured a foot, E, which is commonly called a "chip-breaker," the office of which is readily explained by its technical name; but in order to effectually perform this function the point of the foot or breaker should always be in close proximity to the periphery of the circle described in the revolution of the planer-head with its knives, and as thicker or thinner lumber is presented in the adjusting of the pressure-bar, with its attachment, to its work automacically, the radial movement of the point of the chip-breaker should be concentric to the periphery of the circle made by the revolution. In order to accomplish this we support the pressure-bar, with its chip-board attachment, as follows: G are two arms, to the rear ends of which are secured the pressure-bar D, which in the drawings is represented as having a slot, a, within which is fitted the head b of the chip-breaker. The other ends of these arms are slotted, as shown at c, such slots engaging with the studs d, projecting from the inner face of two circular or semicircular plates, H, the periphery of which is V-shaped, as shown at e, and set-screws h are so arranged as to allow these arms to be adjusted upon the studs d. I are two supports having slots m formed therein, by means of which and suitable bolts such standards are secured to the frame of the machine, one on each side and vertically adjusta-

ble. The top ends of these standards are formed in a circle or semicircle, as shown in Fig. 3, having formed therein a V-shaped channel, *n*, to fit the V-shaped periphery of the plate *H*.
 5 Above the center of this standard, and upon the outer face thereof, projects a support, *J*, from which projects a pin or bearing, *r*, which is the axis upon which the plate *H* has a partially-rotary motion, such bearing fitting in a
 10 suitable recess, *s*, in said plate.
 In Fig. 4 a diagram is shown wherein the radial bars are shown as pivotally secured at a fixed point. Now, if the pressure-bar and its attached chip-breaker are raised by the entering lumber, the higher this rise the nearer the travel of the cutters does the point of the chip-breaker come, and a little more rise will bring it directly into such path to the destruction of the cutters, as the radial movement would be eccentric to the periphery of the circle described by such cutters. In dotted lines above the radial arms are shown as pivotally secured at a higher point, by means of which this difficulty would be partially over-
 15 come; but the entering lumber will now have a tendency to wedge the chip-breaker or drive it forward slightly and prevent its rising above the plane of the lumber. Our device overcomes all these difficulties; we get the
 20 higher pivotal point needed to keep the point of the chip-breaker as it rises nearly concentric with the periphery of the circle described by the rotating cutter-head, and the adjustability of the plate *H* in the top of the stand-
 25 ard rotating about a fixed center enables us to accomplish the desired end.

What we claim as our invention is—

1. In a planing-machine, the combination, with arms having a radial movement from a
 40 fixed pivotal point, which is also adjustable, of a pressure-bar secured to said arms, and a chip-breaker carried by said pressure-bar, substantially as and for the purpose specified.

2. In a planing-machine, circular or semi-circular plates which have a rotary movement 45 around a fixed pivotal point, arms secured at one end to said plates, a pressure-bar secured to the free ends of said arms, and a chip-breaker carried by said pressure-bar, substantially as described.

3. In a planing-machine, and in combination with radial arms carrying a pressure-bar and chip-breaker, the standard *I*, plate *H*, working in the top of said standard, support for said standard, and bracing *r* on said support, substantially as and for the purposes set forth.

4. In a planing-machine, and as a means for securing the radial arms which carry the pressure-bar and chip-breaker attachment, the 6c combination of such radial arms, having slots *c* therein, and provided with adjusting set-screws *h*, with the plates *H*, having lugs *d*, substantially as described.

5. In a planing-machine, and as a means for 65 vertically adjusting the pivotal points of the radial arms which carry the pressure-bar and chip-breaker attachment, the slotted standard *I*, and standards *J*, supporting in the same and carrying the pivotal bearings *r*, in com- 70 bination with the plates *H*, working in the standard *I*, and their connections with such radial arms, substantially as specified.

6. In a planing-machine, the combination, with the standard *I*, having groove *n*, and 75 support *J* for said standard, provided with bearing *r*, of the plates *H*, having V-shaped periphery, and recess *S*, arms *G*, connected with said plates, and the chip-breaker *E*, carried by said arms, substantially as and for the 80 purpose specified.

ALEXANDER C. DUMONTIER.

ARTHUR PLOURDE.
